UNITED STATES PATENT OFFICE

155,539

DESIGN FOR AN ENGRAVING MACHINE

Martin H. Preis, Cranford, and Jakob A. Hoffmann, Lyndhurst, N. J., assignors to H. P. Preis Engraving Machine Co., Newark, N. J., a partnership

Application August 20, 1947, Serial No. 140,952

Term of patent 14 years

(Cl. D64—11)

To all whom it may concern:

Be it known that we, Martin H. Preis, a citizen of the United States, residing in Cranford, Union County, New Jersey, and Jakob A. Hoffmann, a citizen of the United States, residing in Lyndhurst, Bergen County, New Jersey, have invented a new, original, and ornamental Design for an Engraving Machine, of which the following is a specification; reference being had to the accompanying drawing, forming a part thereof:

The figure is a perspective view of an engraving machine, showing our new design.

We claim:

The ornamental design for an engraving machine, as shown.

MARTIN H. PREIS.
JAKOB A. HOFFMANN.
